UNITED STATES PATENT OFFICE

131,204

DESIGN FOR A RUBBER BOOT

George H. Bingham, Jr., Lincoln, Mass., assignor
to Cambridge Rubber Co., Cambridge, Mass., a
corporation of Massachusetts

Application June 13, 1941, Serial No. 101,446

Term of patent 3½ years

To all whom it may concern:

Be it known that I, George H. Bingham, Jr., a citizen of the United States, residing at Lincoln, in the county of Middlesex and Commonwealth of Massachusetts, have invented a new, original, and ornamental Design for a Rubber Boot, of which the following is a specification, reference being had to the accompanying drawing, forming a part thereof, in which

Figure 1 is a side elevation of a rubber boot showing my new design;

Figure 2 is a similar view of the boot shown in Figure 1 but illustrating it with the top open at the side thereof, thus exposing the bellows tongue;

Figure 3 is an elevation of the opposite side of the boot from that shown in Figure 1; and

Figure 4 is a plan view of the boot.

I claim:

The ornamental design for a rubber boot, substantially as shown.

GEORGE H. BINGHAM, JR.
